COFFEE AND SUGAR DISPENSER UNIT

Joseph V. Galbo, Buffalo, N. Y.

Application July 15, 1958, Serial No. 51,794

Term of patent 7 years

(Cl. D44—22)

Fig. 1 is a perspective view of a coffee and sugar dispenser unit showing my new design;

Fig. 2 is a top plan view;

Fig. 3 is a bottom plan view; and

Fig. 4 is a rear perspective view of the same.

I claim:

The ornamental design for a coffee and sugar dispenser unit, as shown.
